UNITED STATES PATENT OFFICE

95,757

DESIGN FOR AN ENSEMBLE DRESS

Jack Kirschner, New York, N. Y.

Application April 11, 1935, Serial No. 56,337

Term of patent 3½ years

To all whom it may concern:

Be it known that I, Jack Kirschner, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The zigzag lines on the front and back of the sleeves of the jacket represent shirring.

The leaf like structures under the shirring on the sleeves of the jacket represent a floral embroidery.

I claim:

The ornamental design for an ensemble dress, substantially as shown and described.

JACK KIRSCHNER.
